UNITED STATES PATENT OFFICE

2,508,394

FRACTIONATING COLUMN

Harry J. John, Philadelphia, Pa.

Application May 10, 1946, Serial No. 668,998

1 Claim. (Cl. 261—95)

(Granted under the act of March 3, 1883, as
amended April 30, 1928; 370 O. G. 757)

1

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

This invention relates to rectifying or fractionating devices including columns or towers and is more particularly concerned with the packing used therein to effect contact between rising vapors and downwardly flowing liquid.

In general, the objects of this invention are to provide packing of the type mentioned which is simple, which effects highly efficient fractionation, high throughput and small H. E. T. P. (height equivalent to a theoretical plate).

These objectives are accomplished in accordance with this invention by providing packing of mesh or screen material in forms which distribute the reflux in thin films over wide areas in the path of the rising vapors in the column and which provide a longer path of travel for the ascending vapors without necessitating an increase in the overall height of the column or tower.

This invention, including some of its possible modifications, is illustrated in the accompanying drawing and described hereinafter, from which a full understanding of the invention may be had and from which other objects and advantages will be apparent.

In the drawing:

Figure 1 is an elevational section of a portion of a fractionating column containing one form of packing in accordance with this invention.

Figure 2 is an exploded view of the packing elements of Figure 1.

Figures 3, 5, 7, and 9 are views similar to Figure 1 showing modified forms of packing elements.

Figures 4, 6, 8, and 10 are exploded views of the packing elements of Figures 3, 5, 7, and 9, respectively.

Referring with more particularity to the drawing in which like numerals designate like parts, the embodiment illustrated in Figures 1 and 2 shows a tubular column 11, wherein packing elements in the form of foraminous discs 12 and 13 are disposed vertically spaced therein. These discs are each fabricated from flat screen material, preferably of a non-corrosive type. An important feature of each disc is that in its normal state it is flat and the diameter is larger than the inside di-

2

ameter of the column 11. When the disc is disposed in the tubular column, it is forced to assume a bowed position to impart thereto a uniform arcuate contour. By these means, the resiliency of the meshed material creates a continuous pressure between the edge of the disc and the wall of the column, thereby holding the disc in place. The edge of the disc under the resilient action of the material also adjusts itself to any irregularities of the column wall and thereby prevents leakage between the disc and wall.

The adjacent discs 12 and 13 have cut-out sections 14 and 15, respectively, extending from the edges of the discs toward the centers, and the discs are disposed in the column so orientated as to locate the cut-out sections approximately on opposite sides of the column. Vertical screens in the form of tabs as shown at 16 and 17 are interposed between adjacent discs, over which the liquid flows from one disc to the other, substantially as illustrated. The rising vapors pass upward through the sections 14 and 15, which cause the vapors to travel back and forth across the column as they rise and to contact the liquid film on the discs and tabs.

Although the mesh of the wire screening from which the discs are made can be varied depending upon the liquid to be fractionated, it will ordinarily be desirable to confine it to the range of 30 to 80 for most reflux liquids.

The embodiment illustrated in Figures 3 and 4 is similar to that shown in Figures 1 and 2, except that the tabs 16 and 17 are not used. Instead, pairs of discs 18 and 19 having diametrically opposite cut-out sections 20 and 21 are bowed in opposite directions and placed in juxtaposition with their concave sides facing each other. This effects a direct physical contact between the two discs for liquid flow and provides a lateral space between the discs for the passage of vapor. Better distribution of liquid dropping from one pair of plates to the next may be effected by the use of distributors 22, as shown in Figures 5 and 6, such as wires or other suitable devices, secured between pairs of adjacent convex surfaces. These distributors may be secured to the discs by welding or otherwise.

Where it is desired further to increase the film area, additional vertical screen material may be interposed between the adjacent discs. In the embodiment illustrated in Figures 7 and 8, discs 24 and 25 without tabs are disposed in the column. The concave and convex surfaces of adjacent discs face each other, and the discs are spaced apart with additional screen devices 26 interposed be-

tween them. The device 28 may be of any suitable form, the devices shown in Figures 7 and 8 being illustrative. In this embodiment, there is also illustrated the use of rings 23 to provide additional support for the discs, if needed, or in case it is desired to use flat discs without bowing or discs that are not resilient. The use of these rings is optional in any event. The rings themselves are split at one point, as shown at 23A, and are slightly larger than the inside diameter of the column so that they can be wedged into the column in a tight fit.

The embodiment illustrated in Figures 9 and 10 employs different forms of discs 27 and 28, the disc 27 having a cut-out section 29 on one side and the disc 28 having a central aperture 30. These discs are spaced apart in alternating relation and between them is disposed a coil of screen material 31 in the form of a clock spring. The discs 27 and 28 abut either side of the coil by means of which vapor enters and is led either into the center of the coil or the outer edge thereof and travels in the opposite direction between the convolutions of the coil before passing upward through the next disc. The vapors pass through one coil in the direction opposite to its immediately preceding coil. By the use of these coils, the path of the vapor is increased many-fold as the vapor rises through the column, and at the same time additional film areas of the reflux liquid are exposed on the screen coil.

In this embodiment of the invention, it is preferable to employ flat discs so that contact therewith is made along the entire edge of the screen coil or else the thickness of the coil may be varied to provide for such contact.

It is to be understood, however, that materials

other than screens or wire gauze may be used, including porous materials. Where any materials are used for the packing to fabricate the discs which are not resilient or flexible enough to wedge them into the column, they may be secured in position by means of the rings 23, illustrated in Figures 7 and 8.

Having thus described my invention, I claim:

A fractionating device comprising a vertical tubular column, foraminous discs vertically spaced therein, each disc being fabricated from screen material, being flat in its normal state, having a diameter larger than the inside diameter of the column, and having a cut-out section extending from the edge thereof toward the center, each disc being disposed in the column in forced bowed position to impart thereto a uniform arcuate contour and with adjacent discs so orientated as to locate the cut-out sections approximately on opposite sides of the column, the resiliency of the discs creating a continuous pressure between their edges and the wall of the column, and vertical screens interposed between adjacent discs.
